UNITED STATES PATENT OFFICE.

D. HEWITT CHISHOLM, OF CHICAGO, ILLINOIS, ASSIGNOR TO PEERLESS KITCHEN BOILER & SUPPLY CO., A CORPORATION OF ILLINOIS.

DESIGN FOR A GASOLENE-LAMP.

No. 38,253.

Specification for Design.

Patented Sept. 25, 1906.

Application filed March 28, 1906. Serial No. 308,572. Term of patent 7 years.

To all whom it may concern:

Be it known that I, D. HEWITT CHISHOLM, a citizen of the United States, residing at Chicago, in the county of Cook and State of Illinois, have invented a new, original, and ornamental Design for Gasolene-Lamps, shown by the accompanying drawings, in which—

I claim—
The ornamental design for a gasolene-lamp, as shown.

D. HEWITT CHISHOLM.
